MANUFACTURE OF TUBULAR TRIMMING

Victor J. Sigoda, Great Neck, N. Y., assignor to Man-Sew Corporation, New York, N. Y., a corporation of New York

Application June 1, 1950, Serial No. 165,555

16 Claims. (Cl. 112—136)

This invention relates to sewing machine attachments for sewing strips of fabric into a turned tubular trimming in which the stitching is concealed and the manner of producing the same whereby the usual feed mechanism of the sewing machine may be simply utilized to draw the turned tubing from the folder after stitching and turning.

Such tubular trimmings are produced by passing a continuous strip of material through a folder so that the strip is folded longitudinally along its centerline and so that the opposite longitudinal edges are in superposed relationship, in which state the edges are seamed together by the stitching mechanism of the sewing machine, following which the sewn tubing is inverted to conceal the stitched edges within the tubing and the finished trimming is drawn from the machine.

The nature and objects of the invention will become apparent from the description which follows, taken in connection with the accompanying drawings, in which:

Fig. 1 is a perspective view of a sewing machine with an attachment embodying the invention mounted thereon;

Fig. 2 is a plan view showing the attachment mounted on a modified throat plate of the machine, the modified presser foot having been omitted to show the rearward disposition of the feed dog with respect to the needle;

Fig. 3 is a front elevation corresponding to Fig. 2, partly in section, taken on line 3—3 of Fig. 2, to show the lift arrangement for a hold-down member which is a feature of the improved attachment;

Fig. 4 is a fragmentary view corresponding to Fig. 3, showing the extreme open position of the hold-down member when the feed bar of the machine reaches its highest position;

Fig. 5 is a schematic view of a strip of fabric to show its path of travel through the folder, the fabric strip being shown as it would actually appear on its passage through the folder, the folder structure having been omitted and the sewn tubing having been partly broken away to illustrate the improved method of producing the trimming so that it may be drawn through the folder by means of the usual feed mechanism of the sewing machine;

Fig. 6 is a side elevation, partly in section taken on line 6—6 of Fig. 1, showing the modified feed members and their position with respect to the needle;

Figs. 7, 8 and 9 are enlarged, cross-sectional detail views taken on lines 7—7, 8—8 and 9—9 of Fig. 3.

The portions of the sewing machine shown in Fig. 1 comprise the usual bedplate 10, the upright 11, the arm 12, and the head 13 which carries the usual needle bar 14 and needle 15 and the presser foot bar 16 supporting the modified presser foot 17, which is raised by the hand lifter 18.

The usual slide and throat plates are replaced by combined plate 20 which is held on the machine by screws 21. Plate 20, as best shown in Fig. 3 has a cutout 22 in which is received a portion of the folder, generally designated as 30, which projects therethrough to form a needle plate

2

36 which lies in the plane of plate 20 and is provided with a hole 37 through which the needle passes during the stitching operation. Groove 24 in plate 20 accommodates a tubular member 32 secured to folder 30. Plate 20 is also provided with slots through which modified feed dog 25 may operate rearwardly of the stitching action. Cutout 22 and groove 24 permit folder 30 to be mounted low down on the machine and close to the hook, thus facilitating cooperation of the stitch forming mechanism as well as affording a minimum of interference to the passage of work and a maximum of freedom to the machine operator.

Feed dog 25 is secured to the usual feed bar 26 by screws 27, and cooperates with modified presser foot 17 to draw the finished inverted tubular trimming rearwardly from the machine in the manner common for most sewing, but which is novel in the manufacture of this type of trimming. As best shown in Fig. 6, these members are mounted to operate some distance rearwardly of the stitching operation but in line therewith.

Folder 30 is secured to plate 20 by screws 31 and disposed so that the fabric strip is fed into the folder at an angle to the line of feed, from one side thereof, rearwardly of the needle action, so that the longitudinally folded strip must move forwardly toward the operator to the stitching mechanism for seaming the superposed longitudinal edges of the strip.

Folder 30 has a tension ladder 33 attached to a channelled guide portion 34 which extends at an angle to the line of stitching. This guide portion 34 abuts a nose piece 35 which is disposed adjacent to, but rearwardly of needle 15. Referring to Fig. 5, in which the folder structure has been omitted for clarity in comprehending how the strip is initially folded, inverted and refolded, sewn, and then reinverted and directed to the feed mechanism of the sewing machine, the portion of the fabric strip shown at the left is the portion which would normally lie within the channelled guide portion 34. As the strip passes through section 34, the line of such movement being indicated by the horizontally disposed arrow at the left, it will be folded along its centerline, lengthwise, progressively as it travels through guide 34 toward the line of stitching.

Nose portion 35 is designed so that such a folded strip may then be turned to travel at a right angle to its former direction of movement, which change in direction is indicated by the vertically disposed arrow. This is accomplished by inverting the folded strip over an edge of nose 35. This edge lies at an angle of forty-five degrees to the initial line of travel of the strip and also to the line of stitching. This inversion is best seen in Fig. 5.

At the inversion, the longitudinal strip edges are refolded lengthwise, and the refolded strip is then fed past the needle 15 (see the relative position of the needle indicated at 15 in Fig. 5), whereupon the edges are seamed together in the well known manner as the tubing travels forwardly toward the operator. If the tubing were to be taken from the machine at this stage, it would have an exposed line of stitching.

Since this is undesirable, the operator inserts the beginning of this tubing into tube 32 with a wire or any other suitable pusher, thereby inverting the tubing, which conceals the stitching. Enough of the inverted tubing is threaded through tube 32 so that the tubing can be acted upon by the feed members 17 and 25, whereupon in running the machine, the finished inverted tubing will be continuously drawn rearwardly from the machine by the action of such feed elements. The arrows in Fig. 5 indicate the second inversion and the rearward feeding of the finished tubing.

Tube 32 is secured to folder 30 so that it lies parallel to the line of stitching, and it extends forwardly of the needle toward the operator for some distance. A circular

member 38 partly surrounds tube 32 to assist in guiding the inverted and refolded strip as it passes about tube 32 forwardly toward and past the needle 15 on its way to be inverted by passing into tube 32. Guide 38 is supplemented by the inner curved surface 39 of holdown member 42.

It will be noted that presser foot 17 differs from the conventional presser foot so that it cooperates with feed dog 25 some distance rearwardly of the stitching operation. Hence, the holdown function normally exercised by the portion of the presser foot that usually surrounds the needle is absent, and accordingly, the work would be free to "float" or ride upwardly and downwardly with the needle. The loss of the holdown function is usually the cause of missed stitches and other defects in the work. Accordingly, a novel element has been provided to perform this function.

Folder 30 carries a support 40, a portion of which 41 is adapted to act as a shaft for a holdown member 42 which is pivotally mounted thereon. Member 42 extends away from shaft 41 over tube 32 and at its free end, it is formed as a clamp portion 46 which cooperates with needleplate 36 to hold the superposed longitudinal edges of the strip from moving with the needle 15. Suitable clearance 49 is provided in clamp portion 46 about the needle 15.

Normally, holdown member 42 is urged downwardly into engagement with needleplate 36 by the tension exerted by spring 44. The tension may be suitably adjusted by rotating a locking collar 45 in which one end of spring 44 is retained.

In order to permit the work to be acted upon by the feed mechanism so that it can be drawn to the stitching mechanism, provision is made to disengage clamp 46 from needleplate 36 in proper timed relationship. A screw stud 50 is threaded into holdown member 42, in which it may be retained in any adjusted position by locknut 51. The lower end of stud 50 rests on a suitable surface of feed dog 25, and accordingly may be raised thereby. When the needle 15 has been withdrawn from the work, feed dog 25 begins to rise in the usual manner, and as it does so, clamp 46 is lifted to the open position shown in Fig. 4, and the work can then be drawn by the feeding mechanism forwardly towards the operator. As the feed dog 25 is lowered for the next stitch, clamp 46 is firmly pressed downwardly on the work by spring 44, and the superposed edges are securely held during the stitching action.

The method and manner of directing the strip through the folder and the arrangement of the folder with respect to the stitching and feed mechanisms are novel. In the prior art, arrangements have been shown whereby the tubular trimming could be produced in a folder and inverted in a tubular portion thereof, as typically in Woehrle, Patent 988,528, of April 4, 1911. In such arrangements, the usual feed members are employed to draw the folded longitudinal edges rearwardly to the stitching mechanism in the conventional manner, following which, the tubing would be inverted and passed through a tubular member resembling 32 hereof. However, the finished tubing would then be drawn by hand towards the operator continually. The rate of production therefor depends upon the endurance of the operator in such arrangements.

Efforts have been made to relieve the operator of this tedious burden, as typically shown in the patents to Seaman, 2,256,792 and 2,256,793, of September 23, 1941. While these disclose arrangements whereby the feed mechanism of the sewing machine may be employed, that of the instant application is simpler and more effective.

This is made possible by a new and unobvious approach to the problem, whereby the folded longitudinal edges of the strip are fed forwardly to the needle, in-

stead of rearwardly as has been consistently done in the prior art.

This change permits the finished tubing to be drawn rearwardly from the machine by means of the usual feed mechanism, with only slight modification. Provision of the holdown member makes for positive operation of the stitching mechanism, and eliminates the possibility of the work "floating" with the needle.

What has been disclosed is an attachment for any conventional sewing machine whereby it can be readily converted to the automatic production of inverted tubular trimming by substitution of the conventional slide and throat plates, presser foot and feed dog with the modified elements described and illustrated herein. Such conversion may be quickly and easily made without impairing the construction or operation of the machine.

While the present preferred embodiment has been described in detail for the purpose of illustration, it is to be understood that the invention is not to be limited to the details of construction shown and described, but is to be construed broadly within the spirit and scope of the appended claims.

What is claimed, is:

1. In a sewing machine, in combination, stitch-forming mechanism, a feeding mechanism including a feed dog, a first presser device including a presser bar and a presser foot carried thereby, said feed dog and said presser foot being arranged and disposed substantially rearwardly of the stitch-forming mechanism but in line therewith, a folder mounted adjacent to and rearwardly of the stitching mechanism adapted to fold and direct a fabric strip along a path angularly intersecting the line of stitching rearwardly of the stitch-forming mechanism and to invert and refold said strip and to direct it forwardly to the stitching mechanism to be seamed thereby into a tubular trimming, a second presser device mounted in operative relation to said folder to cooperate with a surface adjacent the needle hole to hold said strip in fixed position during the seaming operation, means to disengage said second presser device during the feeding of said strip, and means adjacent the needle in which said trimming may be inserted to be inverted following seaming and directed rearwardly past the stitch-forming mechanism to be drawn by said feed members and from the machine.

2. In a sewing machine to produce stitched and turned tubular trimming having stitch forming mechanism, a presser device including a presser bar and a presser foot carried thereby, and a work feeding member cooperating therewith, wherein said presser foot and said feed member are arranged and disposed substantially rearwardly of the stitch-forming mechanism but in line therewith, the combination with a folder mounted adjacent to and rearwardly of the stitching mechanism and adapted to fold and direct a fabric strip forwardly to the stitching mechanism to be seamed into a tubular trimming thereby, means adjacent the needle in which said trimming may be inserted to be inverted and directed rearwardly past the stitch-forming mechanism to be drawn by said feed members, and a holdown member adapted to cooperate with a surface in the vicinity of the needle action to hold the folded strip in position during the stitch-forming operation.

3. In a sewing machine to produce stitched and turned tubular trimming having stitch forming mechanism, a presser device including a presser bar and a presser foot carried thereby, and a work feeding member cooperating therewith, wherein said presser foot and said feed member are arranged and disposed substantially rearwardly of the stitch-forming mechanism but in line therewith, the combination with a folder mounted adjacent to and rearwardly of the stitching mechanism and adapted to fold and direct a fabric strip forwardly to the stitching mechanism to be seamed into a tubular trimming thereby, means adjacent the needle in which said trimming may be inserted to be inverted and directed rearwardly past the

stitch-forming mechanism to be drawn by said feed members, a holdown member adapted to cooperate with a surface in the vicinity of the needle action to hold the folded strip in position during the stitch-forming operation, and resilient means to normally urge said holdown member into engagement with said surface.

4. In a sewing machine to produce stitched and turned tubular trimming having stitch forming mechanism, a presser device including a presser bar and a presser foot carried thereby, and a work feeding member cooperating therewith, wherein said presser foot and said feed member are arranged and disposed substantially rearwardly of the stitch-forming mechanism but in line therewith, the combination with a folder mounted adjacent to and rearwardly of the stitching mechanism and adapted to fold and direct a fabric strip forwardly to the stitching mechanism to be seamed into a tubular trimming thereby, means adjacent the needle in which said trimming may be inserted to be inverted and directed rearwardly past the stitch-forming mechanism to be drawn by said feed members, a holdown member adapted to cooperate with a surface in the vicinity of the needle action to hold the folded strip in position during the stitch-forming operation, resilient means to normally urge said holdown member into engagement with said surface and means to disengage said holdown member from said surface while said feed member is transporting the sewn tubular member.

5. In a sewing machine to produce stitched and turned tubular trimming having stitch forming mechanism, a presser device including a presser bar and a presser foot carried thereby, and a work feeding member cooperating therewith, wherein said presser foot and said feed member are arranged and disposed substantially rearwardly of the stitch-forming mechanism but in line therewith, the combination with a folder mounted adjacent to and rearwardly of the stitching mechanism and adapted to fold and direct a fabric strip forwardly to the stitching mechanism to be seamed into a tubular trimming thereby, means adjacent the needle in which said trimming may be inserted to be inverted and directed rearwardly past the stitch-forming mechanism to be drawn by said feed members, a holdown member adapted to cooperate with a surface in the vicinity of the needle action to hold the folded strip in position during the stitch-forming operation, resilient means to normally urge said holdown member into engagement with said surface, means to disengage said holdown member from said surface while said feed member is transporting the sewn tubular member, said means comprising a member connecting the holdown member and the feed member.

6. In a sewing machine to produce stitched and turned tubular trimming having stitch forming mechanism, a presser device including a presser bar and a presser foot carried thereby, and a work feeding member cooperating therewith, wherein said presser foot and said feed member are arranged and disposed substantially rearwardly of the stitch-forming mechanism but in line therewith, the combination with a folder mounted adjacent to and rearwardly of the stitching mechanism and adapted to fold and direct a fabric strip forwardly to the stitching mechanism to be seamed into a tubular trimming thereby, means adjacent the needle in which said trimming may be inserted to be inverted and directed rearwardly past the stitch-forming mechanism to be drawn by said feed members, a holdown member adapted to cooperate with a surface in the vicinity of the needle action to hold the folded strip in position during the stitch-forming operation, resilient means to normally urge said holdown member into engagement with said surface and means to disengage said holdown member from said surface while said feed member is transporting the sewn tubular member, said means comprising an adjustable stud connected with said holdown member and adapted to contact said feed member.

7. A sewing machine attachment for producing turned tubular trimming having concealed stitching, adapted to be applied to a sewing machine having stitch-forming mechanism, a presser foot, a feed member cooperating therewith, and feed operating means, comprising a base plate to be mounted adjacent the needle, a folder mounted thereon, said folder having means to fold a fabric strip longitudinally along its centerline and to direct said strip along a path angularly intersecting the normal line of feed of said sewing machine rearwardly of the stitch-forming mechanism and means to invert and refold said strip and to superpose the longitudinal edges thereof and to direct said strip forwardly to the stitch-forming mechanism of the sewing machine to be seamed thereby to form a tubular trimming, and a tubular guide member mounted on said base plate adjacent said folder in which said trimming may be inserted to be inverted and directed in a path parallel to the line of stitching whereby said trimming may be drawn rearwardly from the machine by the coaction of the presser foot and feed member.

8. A sewing machine attachment for producing turned tubular trimming having concealed stitching, adapted to be applied to a sewing machine having stitch forming mechanism including a reciprocating needle, and a presser foot and a cooperating feed dog operating substantially rearwardly but in line with the stitch-forming mechanism, comprising a throat plate having a portion cutout in the vicinity of the needle action, a folder mounted on said throat plate having a portion fitting in said cutout adapted to act as a needleplate, said folder having a channel portion adapted to fold a fabric strip longitudinally along its centerline and to direct said strip along a path angularly intersecting the line of stitching of said sewing machine rearwardly of the stitch-forming mechanism, a second portion adapted to invert and refold said strip longitudinally and to superpose the edges thereof in alignment and to direct said refolded strip forwardly to the stitch-forming mechanism to be seamed thereby to form a tubular trimming, a member pivotally mounted on said folder having a portion adapted to cooperate with said needleplate portion of said folder to hold said strip in fixed position during the seaming operation, and a tubular member mounted within said folder in which said trimming may be inserted to be inverted and directed rearwardly whereby it may be drawn from the machine by the coaction of the presser foot and feed member.

9. In a sewing machine to produce stitched and turned tubular trimming having stitch forming mechanism, a presser bar, a presser foot carried by said bar and a feed member, wherein said feed member and said presser foot are disposed rearwardly of the stitch forming mechanism but in line therewith, a throat plate, a folder mounted thereon, said folder having a portion adapted to fold a fabric strip longitudinally along its centerline and to direct said strip along a path angularly intersecting the line of feed of said sewing machine rearwardly of the stitch forming mechanism, a second portion adapted to invert the folded longitudinal edges and to refold the strip longitudinally along its centerline so that the inverted edges are superposed and to turn the refolded strip at an angle to its original path of travel and to direct it to move in a forward direction to the stitch forming mechanism of the sewing machine to be seamed thereby into a tubular trimming, a support mounted on said folder, a holdown member pivotally mounted on said support, said member having a portion adapted to cooperate with a surface in the plane of the throat plate in the vicinity of the needle hole to secure the superposed edges during the seaming, and a tubular member mounted on said folder parallel to the line of stitching in which the tubular trimming may be inserted to be inverted and directed to be drawn rearwardly from the stitch forming mechanism by the coaction of said presser foot and feed member.

10. A sewing machine attachment adapted to be applied to a sewing machine having stitch forming mecha-

nism, a presser device including a presser bar carrying a presser foot, and feed mechanism including a feed dog, said presser foot and said feed dog being mounted for cooperation rearwardly of but in line with the stitching mechanism, comprising a throat plate, a folder carried thereby, said folder having means to fold a fabric strip longitudinally along its centerline and to direct said strip along a path angularly intersecting the normal line of feed of said sewing machine rearwardly of the stitch-forming mechanism, additional means to invert and refold said strip and to superpose the longitudinal edges thereof and to direct said strip forwardly to the stitch-forming mechanism of the sewing machine to be seamed thereby to form a tubular trimming, comprising a channel member mounted parallel to the line of stitching, a tubular member mounted within said channel member and a circular guide partly surrounding said tubular member, a support mounted on said folder, a holddown member pivotally mounted on said support, said holddown member comprising an arm extending across the line of stitching and having a portion thereof adapted to act as a clamp in conjunction with a surface surrounding the needle hole, said portion having an inner surface adapted to complete the circular guide surrounding the tubular member, said tubular member being adapted to receive said trimming to be inverted by insertion therein and to direct said trimming rearwardly past the stitch-forming mechanism to be drawn from the machine by the coaction of the presser foot and the feed dog.

11. A sewing machine attachment adapted to be applied to a sewing machine having stitch forming mechanism, a presser device including a presser bar carrying a presser foot, and feed mechanism including a feed dog, said presser foot and said feed dog being mounted for cooperation rearwardly of but in line with the stitching mechanism, comprising a throat plate having slots through which the feed dog may operate arranged rearwardly a substantial distance behind but in line with the needle action and a cutout portion surrounding the area in which the needle reciprocates, a folder mounted on said throat plate and having a portion fitting into said cutout and adapted to act as a needle plate over which the work passes as it is stitched, a portion of said folder being mounted rearwardly of the stitch-forming mechanism and at an angle to the line of stitching, said portion being adapted to fold a fabric strip longitudinally along its centerline and to direct it to the line of stitching, a second portion adapted to turn and refold said strip and to direct it on a line parallel to the line of stitching toward the stitch-forming mechanism from the rear thereof to seam the folded strip as it passes the stitch-forming mechanism on its way to a tubular member carried by said folder in which the sewn tubing may be inserted to be inverted and directed rearwardly past the stitch-forming mechanism to be drawn from the machine by the coaction of the presser foot and feed dog, a support mounted on said folder, a holddown member pivotally mounted on said support, said holddown member having a clamping portion extending across the line of stitching and adapted to cooperate with the needle plate portion of the folder to secure the work against movement during the stitching operation, resilient means to normally hold said clamping portion in engagement with said needle plate portion of the folder, and means carried by said holddown member whereby it may be disengaged from said needle plate portion by the upward movement of the feed mechanism.

12. The method of producing a turned tubular trimming in which the stitching is concealed, comprising folding a fabric strip longitudinally along its centerline right side out and guiding and directing said folded strip to travel along a path angularly intersecting the line of stitching of a sewing machine rearwardly of the stitch-forming mechanism, turning and directing said folded strip to travel forwardly toward the stitch-forming mech-

anism along a path at an angle to the initial path of travel and at the same time inverting said folded strip and refolding it wrong side out and so that the longitudinal edges are superposed and in alignment to be seamed as the refolded strip is directed toward the stitch-forming mechanism, seaming said superposed edges, inverting the tubular trimming formed thereby right side out, and drawing said trimming in a path parallel to the line of stitching rearwardly past the stitch-forming mechanism.

10 13. In a sewing machine having a needle to stitch material passed thereunder and feed means including a feed dog and a presser foot arranged in line with and disposed substantially rearwardly of the needle, means for folding and directing a fabric strip to the needle to be sewn into tubing and for thereafter inverting said tubing to conceal the stitching therein and for thereafter directing the inverted tubing to said feed means so that the fabric strip may be continuously drawn through said folding and inverting means for such operations, comprising a channel angularly disposed to and intersecting the line of stitching rearwardly of the needle through which a fabric strip may be drawn and folded lengthwise, angularly disposed edges adjacent the outlet of said channel over which the folded fabric strip may be inverted to be directed forwardly to the needle for stitching into a continuous tubing, and a tubular guide mounted within said edges and disposed on a line parallel to the line of stitching having an entry disposed forwardly of the needle and into which the tubing may be inserted to be inverted, and an outlet disposed rearwardly of the needle adjacent to and in position to direct the emerging inverted tubing to the feed members.

15 14. An attachment for producing an inverted, tubular trimming having concealed stitching adapted to be affixed to the cloth plate of a sewing machine having a needle for stitching material passed thereunder and feed means including a feed dog and a presser foot arranged in line with and disposed substantially rearwardly of the needle, comprising a throat plate having a portion cut out in the vicinity of the needle action, and a folder 20 mounted on said throat plate having a portion fitting into said cutout and adapted to act as a needle plate, said folder having means for folding and directing a fabric strip to said needle to be sewn into a continuous tubing and for thereafter inverting said tubing to conceal the sewn edges therein, and for thereafter directing the inverted tubing to said feed means to draw the fabric strip through the folding and inverting means for such operations, comprising a channel angularly disposed to and intersecting the line of stitching rearwardly of the needle through which a fabric strip may be drawn and folded lengthwise, angularly disposed edges adjacent the outlet of said channel over which the folded fabric strip may be inverted to be directed forwardly to the needle for stitching into a continuous tubing, and a tubular guide 25 mounted within said edges and disposed on a line parallel to the line of stitching, said guide having an entry disposed forwardly of the needle and into which the tubing may be inserted to be inverted and an outlet disposed rearwardly of the needle adjacent to and in position to direct the emerging tubing to the feed members.

30 15. In a sewing machine, in combination, stitch-forming mechanism, a feeding mechanism including a feed dog, a presser-device including a presser-bar and a presser-foot carried thereby to cooperate with said feed dog, said feed-dog and said presser-device being arranged and disposed substantially rearwardly of the stitch-forming mechanism but in line therewith, a member mounted adjacent to and rearwardly of the stitch-forming mechanism having one portion adapted to fold and direct a fabric strip along a path angularly intersecting the line of stitching rearwardly of the stitch-forming mechanism, another portion angularly disposed adjacent the first portion to invert and refold said strip and to direct it forwardly to the stitching-forming mechanism to be seamed thereby into a tubular trimming, and a tubular

guide member mounted within the second portion and disposed parallel to the line of stitching, in which guide said trimming may be inserted to be inverted and directed rearwardly past the stitch-forming mechanism to be drawn by said feed members from the machine.

16. Apparatus for producing a turned, tubular trimming in which the stitching is concealed, in conjunction with a sewing machine having stitch-forming and feed mechanisms; comprising, means for folding a fabric strip longitudinally along its centerline right side out; means for guiding and directing said folded strip to travel along a path angularly intersecting the line of stitching produced by said sewing machine rearwardly of the stitch-forming mechanism; means for turning and directing said folded strip to travel forwardly toward the stitch-forming mechanism along a path at an angle to the initial path of travel; said means also being adapted to simultaneously invert said folded strip and to refold it wrong side out with its longitudinal edges superposed and in alinement for

seaming by the stitch-forming mechanism of the sewing machine; said means also being adapted to direct the refolded strip toward the stitch-forming mechanism for seaming thereby; means for inverting the sewn tubular trimming thus formed right side out; said means also being adapted to direct said trimming rearwardly past the stitch-forming mechanism parallel to the line of stitching.
